UNITED STATES PATENT OFFICE.

WALLER CROW AND JOHN C. SCHAFER, OF TIFFIN, OHIO.

FURNACE.

1,291,425.

Specification of Letters Patent. Patented Jan. 14, 1919.

Application filed November 13, 1917. Serial No. 201,822.

To all whom it may concern:

Be it known that we, WALLER CROW and JOHN C. SCHAFER, each a citizen of the United States of America, residing at Tiffin, 5 Seneca county, Ohio, have invented new and useful Furnaces, of which the following is a specification.

This invention relates to furnaces.

This invention has utility when incorporated in furnaces or burners, especially for 10 delivering determined volume of controlled quality heating gases.

Referring to the drawings:

Figure 1 is a fragmentary side elevation 15 of an embodiment of the invention in co-operative combination with a rotary kiln and its cooler;

Fig. 2 is a plan view of the furnace, with parts broken away;

Fig. 3 is a longitudinal section through 20 the furnace of Figs. 1 and 2;

Fig. 4 is a detail view of the ash disposal automatic conveying apparatus;

Fig. 5 is a section through the ash dump 25 device;

Fig. 6 is a detail view, with parts broken away, of the steam control connection for the ash conveyer system;

Fig. 7 is an end elevation, with parts 30 broken away, of the furnace; and

Fig. 8 is an end elevation of the furnace from the opposite or discharge end, as to the showing in Fig. 7, parts being broken away.

The furnace is shown as comprising the 35 housing 1 having outer, intermediate and inner refractory linings backing the arch 2 of the combustion chamber 3, below which is disposed the taper sided ash hopper 4 separated from the combustion chamber by the 40 tiltable grates 5.

The fuel supply or coal storage bin may be connected to the chutes 6 delivering to the stokers 7, which are disposed in a series one along each side of the furnace 1 in opposing 45 pairs, in this instance, instead of staggered. An electric motor 8 (Fig. 7) may actuate one of the stokers 7, and the lower main shaft 9 extend through to drive the aligned stokers 7 of its series.

50 The upper fuel delivery or slow speed shafts 10 of the stokers 7 may carry eccentrics 11 acting through the links 12, angle levers 13, and links 14 to rock the grates 5, thereby automatically assisting in the working of the 55 ash through the grates from the combustion

chamber to the hopper 4. The stokers 7 discharge into the combustion chamber 3 through the lateral openings 15 of the furnace 1, which openings 15 are closed by the doors 16, about the stoker discharge spouts 60 17. Below the stoker discharge spouts, the furnace has openings normally closed by the doors 18, so that access may on occasion be had, as for relieving grate trouble, and inspection. 65

The refuse material from combustion delivered to the ash hopper 4, accumulates on the trap doors, and when of sufficient quantity to overcome the closing action of the adjustable counterweights 20, opens the trap 70 doors 19. Rigid with each door 19 is the vane 21, so that in the opening the air lock of the disposal system or apparatus in the supplementary hopper 22 is broken, and the gates 19 may readily recover upon discharge 75 of the ash. Connected to be actuated automatically by the opening of the doors 19, through the links 23, 24, is the valve 25 in the steam line 26 extending to the steam unit 27 for effecting removal of the ash from 80 hopper 22 in the duct 28 for travel in the duct 29 (Fig. 4.) The trap doors 19 on the shafts 31 are connected by the segmental gears 32 for simultaneous rocking in opening and closing. 85

The heating gases from the combustion chamber 3 pass through the large cross-sectional area opening 33 above the bridge wall 34 (Figs. 2, 8) for delivery into the registering opening 35 (Fig. 3) of the rotary kiln or 90 treating member 36, from which the gases expending their heating action or completing combustion, may pass by the flue 37.

The heat treated material from the rotary kiln 36 may be discharged from the opening 95 35 to fall into the way 38 onto the gates 39 having the threaded rod extensions 40 carrying the sprocket wheels 41 connected by the sprocket chains 42 with the crank carrying sprocket wheels 43, so that there may be 100 accurate control of the discharge from the kiln 36, or that the flow through the way 38 may be regulated to conform to the capacity of the kiln 36, in the removal of treated material to the rotary cooler 44. 105

The hot material in the rotary cooler 44, may have cooling air drawn thereover by providing the chamber 45 in communication with the air discharging end of the cooler 44. Lateral passages 46 from the chamber 110

45 communicate with the tunnels 47. From these tunnels 47 extend ducts 48 as controlled by the dampers 49 in supplying hot air to the furnace 1 below the grates 5. For additional combustion-supporting-hot-air-supply, the ducts 50 shown in Figs. 2, 7, as extending down into the masonry over the tunnels 47 may extend to the combustion chamber 3 above the grates 5. The air supply of these ducts 50 may also be regulated by the pull out dampers 51 (Fig. 2.) This mode of utilization of the heat permits operation with maximum of economy in this closed-furnace-draft-circulation-system. To temper the heat of the combustion chamber as well as accelerate the draft, valves 52 may control steam lines 53 discharging into the ducts 48 as injectors. This combustion-supporting-gas supply below the grates 5, with the intermittent shifting of grate-carried-material insures rapid and complete combustion of the fuel.

The shield 54 detachably bolted to the furnace reduces the escape of hot gases adjacent the kiln 36, while removal of this shield permits shifting of the furnace 1 by allowing it to travel on its wheels 55 along the tracks 56 away from the kiln 36, so ready access to the kiln and combustion chamber may be had, as for upkeep, through the large registering openings. In this shifting of the furnace 1, the material chute 38 is opened at its self-closing joint 57 (Fig. 3.) The ash hopper disconnects from the trap doors at the joint 58, (Fig. 3) and the hot air ducts 48, 50, disconnect at the joints 59, (Figs. 3, 7) in the out of use shifting of the furnace 1.

With the furnace in operation, it will maintain a desired quality and volume-heating-gas-supply with a minimum of attention and a maximum of fuel economy.

Instead of the production of an oxidizing flame or oxidizing combustion gases for introduction through the large discharge opening of the rotary kiln, the heating gases may have their combustion proportioned to fall more or less short of complete combustion, thereby retarding the complete combustion until along in the kiln 50 thereby distributing the heat and tempering the initial intensity for a given supply or volume. This delicacy of adjustment, even up to full combustion in the combustion chamber 2 may be regulated not only by the heated air supplies through the ducts 50, but there may be supplemental regulation thereof to permit intake of unheated air through the openings 60 in the flange projection 61 from the ducts 50. The cap 62 (Figs. 2, 3) may be rotated to bring its openings 63 along its cylindrical portion more or less out of registry with the openings in the pipe 50 to effect this cooling air control. Further, the duct 64 may enter the combustion chamber 2 adjacent the bridge

wall 34, to temper or lower the heat intensity at the kiln entrance, by the control 60, 61, 62, 63, or for unmixed-heated-air-supply.

As a temperature checking up means assisting in fixing the conditions it is desired prevail at the furnace as well as through the kiln, pyrometers 65 are installed.

What is claimed and it is desired to secure by Letters Patent is:

1. A furnace provided with a combustion chamber, a lateral fuel receiving opening therefor, an ash hopper, grates separating the combustion chamber from the ash hopper, a stoker disposed for delivering fuel into the combustion chamber through the fuel receiving opening, said stoker being provided with means for actuating the grates, and an automatic dump for the hopper provided with a conveyer and controlling means therefor for removing the dumped material.

2. A furnace provided with a combustion chamber, two series of lateral fuel receiving openings therefor, stokers disposed at said openings, an ash hopper, grates separating the hopper from the combustion chamber, and driving means for the stokers connected to actuate the grates.

3. A shiftable furnace including a supporting way along which the furnace may travel, said furnace including a combustion chamber provided with a heating gas discharge, and a bridge wall between the chamber and said discharge inclined to deflect gas flow upwardly from the discharge.

4. A shiftable furnace including a supporting track way therebelow along which the furnace may travel, said furnace being provided with a combustion chamber having a heating gas discharge disposed in the line of said way.

5. In an installation including a treating chamber member provided with a heating-gas-receiving-opening, a furnace shiftable to position adjacent said opening, said furnace being provided with a combustion chamber having a discharge opening for registering with the treating member opening, and an interfitting shield member shiftable with the furnace permitting rotation of the member as to the furnace when the furnace and member openings are in register.

6. In an installation including a treating member provided with a heating gas receiving opening, a furnace provided with a combustion chamber having a discharge opening into said receiving opening, a cooling member for material treated in the treating member, and a plurality of ducts for creating circulation from the cooling member to the combustion chamber and delivering heated combustion supporting gases to the combustion chamber.

7. In an installation including a treating

chamber member and a cooling chamber member to which the treating chamber member may deliver heated material for cooling, a furnace provided with a combustion chamber connected to supply heating gases to the treating member, grates in said furnace below the combustion chamber, and controllable-duct-connection from the cooling member to above and below the grates for supplying combustion-supporting-heated-gases to the furnace.

8. In an installation including a rotary

15 kiln having its discharge end open approximating the diameter of the kiln, a furnace provided with a combustion chamber registering with the kiln discharge end to provide heating gas flow into the kiln throughout the cross-sectional area of the kiln discharge end, said furnace shiftable toward and from the kiln and having a discharge 20 way for the kiln.

In witness whereof we affix our signatures.

WALLER CROW.

JOHN C. SCHAFFER.
